Primary Examiner — Jae Liang*Assistant Examiner* — Bryan Coauhtemoc Gusman(57) **CLAIM**

The ornamental design for a car seat cover, as shown and described.

DESCRIPTION

FIG. 1 is a front, top and right side perspective view of a car seat cover, showing my new design in an installed position of use;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a rear view showing the car seat cover of FIG. 1 in an alternate, uninstalled position.

The thin broken lines in the drawings illustrate environmental subject matter, which form no part of the car seat cover. The thick broken lines in FIG. 7 illustrate portions of the claimed design, which form no part of the claimed design. All other thick broken lines illustrate stitching and are part of the claimed design.
